Primary Examiner — Nathan M Johnston

(57) **CLAIM**

The ornamental design for a handheld drug delivery device as shown and described.

DESCRIPTION

FIG. 1 is a perspective view showing a new design for a handheld drug delivery device with its needle shield in an extended position;

FIG. 2 is a front view of the handheld drug delivery device of FIG. 1;

FIG. 3 is a rear view of the handheld drug delivery device of FIG. 1;

FIG. 4 is a right-side view of the handheld drug delivery device of FIG. 1;

FIG. 5 is a left-side view of the handheld drug delivery device of FIG. 1;

FIG. 6 is a top view of the handheld drug delivery device of FIG. 1;

FIG. 7 is a bottom view of the handheld drug delivery device of FIG. 1;

FIG. 8 is a perspective view of the handheld drug delivery device of FIG. 1 with its needle shield in a retracted position;

FIG. 9 is a front view of the handheld drug delivery device of FIG. 8;

FIG. 10 is a rear view of the handheld drug delivery device of FIG. 8;

FIG. 11 is a right-side view of the handheld drug delivery device of FIG. 8;

FIG. 12 is a left-side view of the handheld drug delivery device of FIG. 8;

FIG. 13 is a top view of the handheld drug delivery device of FIG. 8; and,

FIG. 14 is a bottom view of the handheld drug delivery device of FIG. 8.

The broken lines showing portions of the design are included for the purpose of illustrating portions of the design that form no part of the claimed design.

1 Claim, 8 Drawing Sheets
